INTERNAL COMBUSTION ENGINE

Romeo M. Nardone, East Orange, N. J.

Application November 25, 1939, Serial No. 306,158

2 Claims. (Cl. 123—117)

This invention relates to hydraulic systems, and particularly to the operation of hydraulic mechanism for use in controlling combustion in an internal combustion engine.

An object of the invention is to provide a novel, common speed responsive control of the hydraulic supply means for operating the combustion controlling devices.

A second object is to provide novel, common heat responsive means for regulating the supply of operating fluid to the separate (but co-acting and complementary) combustion controlling devices.

As shown, the combustion controlling devices are two in number—one for actuating the engine throttle, the other for changing the time of ignition in relation to piston position—but it is to be understood that additional hydraulically actuated combustion controls may be provided as substitutes for, or supplements to those illustrated and described.

Other objects are to provide novel hydraulically actuated combustion controlling devices, novel flow directing means associated therewith, and novel means utilizing, as the motive fluid, the same oil supply as that which lubricates the engine driven shaft constituting the common drive means for the engine fuel pump and magneto.

Further objects will become apparent from inspection of the following specification when read with reference to the accompanying drawings wherein is illustrated the preferred embodiment of the invention. It is to be expressly understood, however, that the drawings are for the purpose of illustration only, and are not designed as a definition of the limits of the invention, reference being had to the appended claims for this purpose.

In the drawings,

Fig. 1 is a transverse sectional view of an engine crank-case, with the present invention shown in the relation thereto which it occupies in the preferred embodiment;

Fig. 2 is a transverse sectional view of the thermostatic, or heat responsive device for regulating the supply of operating fluid to the combustion controlling devices;

Fig. 3 is a longitudinal sectional view along the line 3—3 of Fig. 2;

Fig. 4 is a view, partly in elevation and partly in longitudinal section, of the throttle actuating unit;

Fig. 5 is a view in longitudinal section of the preferred form of fuel pump; and

Fig. 6 is a view in longitudinal section of the preferred form of spark advancing and retarding unit for the magneto shown in Fig. 1.

Referring first to Fig. 1, reference characters 11 and 12 designate a pair of spur gears adapted to be rotated by spur pinion 13 secured to or integral with a driving shaft 14 which may be a part of the engine crankshaft or a member driven by the engine crankshaft. As shown the spur gears 11 and 12 are located in the end portion 15 of the supporting frame 16 of the engine, and are formed as integral parts of valve actuating shafts 8 and 9 respectively, the latter being disposed in parallelism with wall 16 of the oil receiving chamber of the engine, said chamber being located directly below the cylinders of the engine, the latter being not shown. Intermediate its ends shaft 8 has an eccentric portion 29 engageable with a reciprocable follower element 31 adapted to actuate the pumping elements of the fuel pump 28 shown in detail in Fig. 5, and at its opposite end the shaft 8 is provided with a spiral gear 32 adapted to actuate a correspondingly formed spiral gear 33 for rotation of the rotor element of the magneto 34. Shaft 9 is shown coupled by suitable means 36 to drive the motor element of an oil pump 22 which provides the pressure for circulation of oil for lubrication of the rotating engine parts as well as for the actuation of the combustion controlling devices hereinafter described in further detail. As shown the oil delivered by the pump 22 enters the hollow interior 37 of the shaft 9 by way of the intervening supply tube 38, and from the space 37 lubricating oil is fed laterally by way of conduit 39 into the hollow interior 41 of the shaft 8 and along said shaft as far as the end portion 42 thereof, and serves to lubricate all intervening surfaces requiring lubrication. Likewise oil is fed along the interior of shaft 9 for lubricating purposes and also for actuation of the combustion controlling devices by the supply of actuating oil under pressure thereto, the rate of supply and the time of supply to said devices being under the control of a reciprocable valve element 43, the movement of which is controlled by the actuating fingers 44 of centrifugal weights 26 constituting, in conjunction with the opposing spring 46 and the fixed and movable collars 47 and 48 respectively, the major elements of the speed responsive device controlling the flow of actuating fluid from the source 37 to the combustion controlling devices by way of the conduit 30 which passes from the valve chamber 49 to the supply chamber 27, shown in Fig. 2, of the

thermostatic unit 35, now to be described in detail.

As shown in Figs. 2 and 3 the thermostatic unit includes a cylindrical valve element 26 adapted to be moved longitudinally by a rod (not shown) extending through and engaging the base of the bellows element 51, and operating in opposition to a compression spring 52 located at the opposite end of the valve, the bellows element 51 being adapted to seal the cup 24 against leakage of the mercury or equivalent fluid contained therein, which fluid expands to a material degree in response to rises in temperature. As shown the cup 24 is suspended in a chamber 53 in such manner that substantially the entire surface of the cup is exposed to contact with the oil delivered thereto by way of the supply chamber 27 above referred to, the connecting passages between the supply chamber 27 and the chamber 53 being indicated at 23 and 23a. Since this oil is supplied, under the control of the valve 43, from a source 37 within one of the major elements of the engine it follows that changes in the temperature of the oil will be in direct proportion to changes in the temperature of the metallic elements such as the shaft 9 of the engine, and that accordingly movement of the valve 26 will be such as to reflect accurately the change in thermal conditions within the engine. However, with the valve 26 in the position shown the oil circulating around chamber 53 will find an outlet independent of the combustion controlling devices 50 and 54, said independent outlet being by way of passages 21, 19 and 18, the passages 19 and 18 being in communication one with the other by way of the peripheral port 17 of the valve 26. From passage 18 the oil returns to the oil receiving chamber 16 of the engine by way of the return passage 18a which registers therewith as indicated in Fig. 1. When however, the engine has warmed up sufficiently so that the corresponding rise in temperature of the oil surrounding the cup 24 causes a sufficient amount of expansion of the mercury, the resulting upward movement of the valve 26 closes off communication between the passages 19 and 18 and the oil is then forced to flow out by way of the outlet 40 which leads to the two combustion controlling devices 50 and 54 by way of the connecting conduits 58 and 59 respectively indicated in Fig. 1. That portion of the oil flowing through conduit 58 will enter the unit 50 at the top of the cylindrical portion thereof and will act upon the piston or plunger element 61 (Fig. 6) to produce a downward movement thereof against the opposition of the compression spring 63, the lower end of which has abutment upon the transverse wall 64 which (together with sealing bellows 62) separates the oil receiving portion of the control unit 50 from the lower chamber 65 into which extends the throttle actuating arm 66 by which the throttle 67 is shifted to a degree corresponding to the amount of movement of the piston 61, thus regulating the amount of combustible mixture supplied to the intake manifold, the fuel supply to the carburetor 68 being by way of the supply conduit 69 leading from the fuel pump 28 heretofore referred to.

That portion of the oil which flows through conduit 59 will enter the combustion controlling unit 54 at the base thereof as indicated at 71 in Fig. 6 and will act upon the lower side of the piston 70 to cause upward movement thereof against the opposition of the compression spring 78, thereby producing a corresponding movement of the piston rod 72 and the rocker arm 73 oper-

atively connected thereto as indicated at 74, the said rocker arm having a fulcrum in a form of bracket 76 extending out from the upper surface of the cover plate 77 of the unit 54. At its outer end rocker arm 73 receives a link 79 as indicated at Fig. 1 and by reason of said link and its connection with the outer end of the spark adjusting arm 80, controls the time of occurrence of the igniting spark in the successive cylinders of the engine, in proper relation to the positions of the pistons therein, and functions to advance the time of such igniting spark as soon as the starting of the engine creates the proper speed, temperature and pressure relationships which are reflected in the operation of the elements 26, 51 and 70 respectively. The piston 70 is thereupon raised promptly to its upper limit, and hence further shift in the position of the spark controlling arm 80 is prevented as long as the engine continues to run. When the engine stops the oil is returned to the chamber 16 by way of port 71 and conduit 59 as indicated in Fig. 1—the pressure in said conduit 59, during normal running of the engine, being sufficient to prevent dropping back of the piston 70 prior to stopping of the engine, and the resultant pressure drop.

In the carburetor, as shown in Fig. 4, there is incorporated an automatic pressure responsive air flow control for auxiliary air intake 81, so that said intake 81 may function to increase the air-to-fuel ratio, in manifold 82, when the engine has warmed sufficiently, thus supplementing the action of throttle 67 and its actuating means. As shown, this flow control is in the nature of a port 83 adapted to be closed by a spring 86 which acts upon the underside of piston valve 81 to move the latter into abutting relation to ported plug 88, thus cutting off communication between port 83 and intake 81. Since flow through intake 81 is thus initially prevented, the only initial path for air flow is by way of the main passage 89, containing throttle 67; thereafter the air-to-fuel ratio in passage 89 (hence in manifold 82) is increased by an amount corresponding to the amount of air that can pass through port 83 to intake 81. This increase in air-to-fuel ratio tends to thin out the mixture automatically after starting, that is, when manifold pressure is reduced sufficiently so that spring 86 is no longer able to prevent an opening of the valve 81 by the atmospheric pressure acting thereon.

In fuel pump 28 (Fig. 5) the delivery stroke is produced by a spring 101 acting on one side of a diaphragm 102 to expel liquid fuel from the pump chamber 103. Cam-operated linkage 31, 105, 106, 107 moves the diaphragm against the action of the spring 101 to energize said spring and produce a suction stroke by which additional liquid fuel is brought into the chamber 103, by way of inlet passages 108 and 109, perforated valve 111 (having the usual pressure responsive cover adapted to open against spring 129) and port 112. The liquid expelled past a similarly constructed perforated outlet valve 113 and a second ported member 114 enters outlet chamber 116 with which novel elements, now to be described, are associated.

To impart initial head to the liquid fuel supply, chamber 116 is provided with a "priming" plunger 117 having a flange 118 at its base to receive a bellows element 119, and a neck portion 121 to receive a manually operable knob or head 122. A pin 123 extends through the neck 121 to receive a rod 124 whose lower end is engageable with the upper extremity of the dia-

phragm assembly to cause downward movement of the said assembly. Spring 126 abuts a fixed plate 127 at one end, and bears upon plunger 117 at its upper end to return the plunger to the position shown after each priming stroke. If the priming action should proceed long enough to create more pressure than is desired, such excess pressure will prevent further lifting of valve 111, and therefore intake of fuel through passage 108 will cease, until such time as the pressure is relieved by way of carburetor supply line 69, due to the starting of the engine. Bellows 119 serves to seal the unit against the possibility of escape of fluid by any path other than the normal outlet 69.

In installations recently made under applicant's supervision it has been found that the unit 54 will function substantially as desired by connecting supply line 59 directly with the interior of shaft 8 or shaft 9, so that oil under pressure will be supplied to unit 54 independently of the valve element 43 and unit 35; nevertheless the combining of the feeds 58 and 59 in the manner indicated is desirable as a means of coordinating and centralizing the control, particularly in the event of use on power plants where access to the shaft interiors is not available to the same degree as indicated in the present embodiment. However, with either of the two indicated methods of connection for feed 59, the result is the same:—a movement of spark advancing lever 80 to "full advance" position promptly upon attainment of normal running conditions. As a means of relieving any possible excessively high pressure after the piston 70 has moved upwardly to the full advance position of lever 80, a by-pass 93 connecting with a return oil line 94, may be provided as shown in Fig. 6 and Fig. 1.

This application is a division of my application No. 215,669, filed June 24, 1938, now Patent Number 2,205,047.

What I claim is:

- 5 1. In a hydraulic system for actuation of a combustion controlling device, such as an electrical contact shifter for establishing the time of ignition of the combustible mixture in relation to the positions of the parts to be actuated by the combustion of said combustible mixture, the combination with said contact shifter of means for actuating said shifter, said means including a piston mechanically linked to said contact shifter, a cylinder housing said piston, means connecting said cylinder with a source of fluid supply, means responsive to operation of the engine for producing flow of fluid from said source to said cylinder, and means integral with said cylinder for relieving excess pressure created therein after the piston has moved sufficiently to shift said contact shifter to the "full advance" position wherein ignition occurs in that relationship to engine crankshaft position that has been preselected as most desirable during normal operation.
- 15 2. In combination with a magneto for delivery of ignition current to an internal combustion engine, means including an engine driven shaft for rotating said magneto, means including a fluid operated piston for controlling the time of delivery of the ignition current from the magneto to the engine, and means including a second shaft rotatable in synchronism with said first named shaft for directing operating fluid to said ignition controlling piston.
